EXTENSION TABLE

James F. Eppenstein, Chicago, Ill.

Application August 4, 1953, Serial No. 26,268

Term of patent 3½ years

(Cl. D33—14)

To all whom it may concern:

Be it known that I, James F. Eppenstein, a citizen of the United States, residing at Chicago, in the county of Cook and State of Illinois, have invented a new, original, and ornamental Design for an Extension Table, of which the following is a specification, reference being had to the accompanying drawing, forming part hereof.

In the drawing:

Fig. 1 is a perspective view of an extension table embodying my new design.

Fig. 2 is an end elevational view of the table of Fig. 1.

Fig. 3 is a side elevational view thereof showing the table extended, with the dotted line showing being for illustrative purposes only.

I claim:

The ornamental design for an extension table, as shown and described.
